UNITED STATES PATENT OFFICE.

DAVID HENRY MARSHALL, OF KANSAS CITY, MISSOURI, ASSIGNOR OF
ONE-HALF TO LAWERENCE E. MARSHALL, OF HARTFORD CITY,
INDIANA.

AUTOMATIC CAR-ANNUNCIATOR.

No. 829,080.

Specification of Letters Patent.

Patented Aug. 21, 1906.

Application filed October 2, 1905. Serial No. 281,010.

To all whom it may concern:

Be it known that I, DAVID HENRY MARSHALL, a citizen of the United States, residing at Kansas City, in the county of Jackson and State of Missouri, have invented a new and useful Automatic Car-Annunciator, of which the following is a specification:

My invention relates to certain new and useful improvements in car-annunciators, and has for its object to provide an annunciator that will indicate the street or station as approached automatically.

Another object of my invention is to provide an annunciator that is especially adapted to be used on cars operated by electricity.

A further object of the invention is to provide an alarm in connection with the annunciator, so that the passengers will be notified when the name of a street appears in the annunciator.

With these objects in view my invention consists of the novel features of construction and combination of parts, hereinafter described, and pointed out in the claims.

In the drawings forming a part of the specification, Figure 1 is a sectional view through a car, showing the annunciator in place. Fig. 2 is a front view of the annunciator with the front removed. Fig. 3 is a side view of the annunciator with one side removed. Fig. 4 is a front view of the guideway carrying the block. Fig. 5 is a sectional view taken on the line 5-5 of Fig. 4. Fig. 6 is a transverse section of the guideway, showing the supporting-frame partly broken away. Fig. 7 is a detail view of my improved trolley and its connections, and Fig. 8 is a detail view of the trolley.

Referring to the drawings, A indicates the box inclosing the annunciator, which is provided with the ordinary sight-opening A', arranged in the front and being protected by a pane of glass A''. Secured in the casings are the uprights B and B', connected together by the bars B³ and the bolts B⁴. Mounted in the uprights B and B' are the shafts C and C', provided with rollers C² and C³, carrying the belt C⁶, which passes over the bars B³ and having the names of the streets or stations printed thereon. The ends of the shafts extend through the uprights B' and are provided with gear-wheels C⁴ and C⁵, meshing with a large gear-wheel D, journaled on the shaft D', secured in the uprights B'. The

outer face of the wheel D is provided with 55 outwardly-projecting lugs D for the purpose hereinafter described. Extending out from the uprights B' are bolts E, carrying the frame E', which is provided with the guideway F, slidably mounted on the upper and 60 lower bars of the frame E'. The guideway F consists of a flat plate F', having its ends F² bent in the form of a tube fitting over the bars of the frame E', as shown in Fig. 5. The sides F³ adjacent the ends F² are cut in- 65 wardly at F⁴ and are bent upwardly at F⁵ and inwardly at F⁶. The plate is provided with an outwardly-projecting wrist-pin F⁷, carrying the shifting-lever F⁸, so that the plate F' can be adjusted to either end of the frame E' 70 desired. Sliding in the guideway F is a block G, having an arm G' extending therefrom and outwardly-extending shoulders G², provided with grooves G³, fitting over the inwardly-projecting sides F⁶ of the plate F'. 75 The block G is provided with an opening G⁴, in which is mounted a pivoted pawl G⁵, adapted to engage the lugs D² of the gear-wheel D on its upward stroke and revolve the said wheels. 80

Secured to the bolts B⁴ is a bracket H, carrying a double solenoid-magnet I, having a double core or armature I' co-operating therewith, to which is pivotally connected a rod I², the other end of which is pivotally connected to the arm G' of the block G. The magnet I and armature I' are provided with contact-plates I³, which are connected by wires I⁴ to the battery J and bell K, so that when the armatures are drawn up the circuit 90 will be completed through the plates and the bell will ring, notifying the passengers that a street or station is near. This current for exciting the solenoid may be derived from any means desired; but I preferably employ 95 a contact-shoe L, carried by the trolley-wire M, having a horizontal portion L', adapted to engage the contact-piece N', carried by the fork N² of the trolley-pole N. Connected to the contact-piece N is a conductor O, which 100 passes down the trolley-pole N through the solenoid and is grounded through the wheel and track.

The operation of the device is as follows: 105 A contact-shoe L is placed on the trolley M, near each of the streets or stations that are printed on the belt C⁶. As the car comes along the contact-piece N' comes in contact

with the shoe L, and the current is carried down through the conductor O and through the solenoid I to the ground. The solenoid, being excited by the current, pulls upon the 5 armatures I', which raise the rod I², and with it the block G, carrying the pawl G⁵, which engages the lug D², causing the belt C⁶ to be wound upon one roller and off the other, thus causing the names of one street or station to 10 disappear and that of the next one to appear, and at the same time the bell will ring.

From the foregoing description it will be seen that I have provided means for rewinding the belt on the rollers, as it can be readily 15 seen by shifting the plate F' to the other side of the frame, the pawl G⁵, carried by the block G on its upward stroke, will revolve the gear-wheel D in an opposite direction.

Having thus fully described my invention, 20 what I claim as new, and desire to secure by Letters Patent, is—

1. The combination in a car-annunciator, of rollers carrying a belt, gear-wheels for operating said rollers, a gear-wheel provided 25 with lugs and meshing with the gear-wheels, a guideway slidably mounted on a frame, a block sliding in said guideway, a pawl carried by said block, and means for operating the said block, for the purpose described.

30 2. The combination in a car-annunciator of a casing having shafts mounted therein, carrying-rollers, a belt mounted on said rollers, gear-wheels carried by said shafts, a gear-wheel provided with lugs and meshing with 35 said gear-wheels, a frame arranged adjacent said gear-wheel, a plate slidably mounted on said frame, a vertically-reciprocating block mounted on said plate provided with a pawl and a lever connected to said plate, for the 40 purpose described.

3. The combination in a car-annunciator, of rollers carrying a belt, gear-wheels carried by said rollers a gear-wheel meshing with 45 said gear-wheels, a frame arranged to one side of said gear-wheel, a plate slidably mounted on said frame, a block slidably mounted on said plate, carrying a pivoted pawl adapted to engage lugs arranged on said gear-wheel, means for operating said block 50 together with means for shifting said plate, for the purpose described.

4. The combination with a casing provided with a sight-opening, of a frame arranged in said casing, rollers arranged in said 55 frame above and below said sight-opening carrying a belt, gear-wheels arranged on the end of said rollers, outside the frame, a gear-wheel provided with outwardly-projecting lugs mounted on said frame meshing with 60 said gear-wheels, a frame arranged to one side of said gear-wheel, a plate slidably

mounted on said frame, a vertically-reciprocating block mounted on said plate, provided with a pawl adapted to engage the lugs of said gear-wheel, and a solenoid-magnet arranged in said casing above said frame connected to said block, for the purpose described. 65

5. The combination with a casing provided with a sight-opening, of rollers arranged above and below said opening, provided with gear-wheels at one end, a belt arranged on said rollers, a gear-wheel meshing with said gear-wheels provided with lugs on its outer face, a frame arranged to one side of 70 said gear-wheel carrying a sliding plate, a block carried by said plate provided with a pivoted pawl, means connected to said block for raising said block, and means connected to said plate for shifting said plate, for the 75 purpose described.

6. In a device of the kind described, the combination with a casing provided with a sight-opening, rollers arranged in said casing above and below said opening, carrying a 80 belt, gear-wheels arranged on one end of each of said rollers, a gear-wheel provided with lugs on its outer face meshing with said gear-wheels, a frame arranged to one side of said gear-wheel, a plate loosely mounted on said 85 frame, guideways formed on said plate, a block mounted in said guideways, provided with a recess, a pawl pivoted in said recess, means connected to said block, for bringing said pawl into engagement with said lugs on 90 said gear-wheel, and a lever connected to said plate for shifting the plate on the frame, for the 95 purpose described.

7. The combination in a car-annunciator of a casing provided with a sight-opening, a 100 frame arranged in said casing, rollers mounted in said frame above and below said sight-opening, a belt mounted on said rollers, gear-wheels secured to one end of said rollers, a gear-wheel mounted in said frame meshing 105 with said gear-wheels, lugs formed on the outer face of said gear-wheel, a frame carried by said frame and spaced therefrom provided with parallel longitudinal members, a plate slidably mounted on the horizontal members 110 of the last-mentioned frame, guideways formed on said plate, a block provided with grooved side edges mounted in said guideways having an opening formed therein, a pawl pivoted in said opening, a lever pivoted to said plate, a magnet arranged in said casing, and a rod connecting said magnet to said plate, for the purpose described. 115
